UNITED STATES PATENT OFFICE.

EDWARD E. HINRICHSEN, OF NEW YORK, N. Y., ASSIGNOR, BY MESNE ASSIGNMENTS, TO WESTERN ELECTRIC COMPANY, INCORPORATED, A CORPORATION OF NEW YORK.

TELEPHONE SIGNALING SYSTEM.

1,230,578.

Specification of Letters Patent. Patented June 19, 1917.

Application filed July 19, 1915. Serial No. 40,687.

To all whom it may concern:

Be it known that I, EDWARD E. HINRICHSEN, a citizen of the United States, residing at New York, in the county of New York and State of New York, have invented certain new and useful Improvements in Telephone Signaling Systems, of which the following is a full, clear, concise, and exact description.

10 This invention relates to telephone systems, and more particularly to a supervisory means associated with a link circuit at a central office.

In accordance with this invention there is 15 provided a signaling device forming a part of the link circuit, said device being capable of giving a plurality of signals by varying the strength of current used to operate said device. Such a signaling device may comprise a supervisory lamp in an operator's cord circuit so arranged that the flow of current therethrough may be controlled in such a manner as to give distinctive indications for different circuit conditions.

25 This invention is illustrated diagrammatically in the accompanying drawing.

Subscribers' substations A and B are connected by means of line wires 1 and 2 to a line jack 3 located at the central office. The 30 usual line equipment, comprising a line relay 4 controlling a line lamp 5 and a cut-off relay 6, is associated with each of these lines. There is provided at the central office an operator's cord circuit which includes a 35 source of current, an answering plug 7 and a calling plug 8, and has connected in the talking strands supervisory relays 9 and 10 respectively.

Upon the initiation of a call by subscriber 40 A, the line relay 4 is energized in the usual manner, effecting the lighting of the line lamp 5. The operator, observing the lighted condition of line lamp 5, inserts the answering plug 7 into the line jack 3, thereby causing the operation of cutoff relay 6 and supervisory relay 9. The relay 9 in pulling up its armature closes contact 12, which completes a circuit through relay 13 over the following path: battery, lamp 14, contact 12, conductor 15, coil of relay 13, conductor 16, contact 17 to ground. The actuation of the relay 13 automatically connects the operator's telephone set in the cord circuit. It may be mentioned here that due to the high 55 resistance of the winding of the relay 13,

the lamp 14 is prevented from lighting upon the closure of the circuit just described.

Assuming that subscriber A desires to converse with subscriber B, the operator upon learning of this fact inserts the calling plug 60 8 into the line jack 3. By this operation ringing current is automatically impressed upon the called subscriber's line by the energization of the ringing relay 18 over the following path: battery, lamp 19, conductor 65 20, contact 21, conductor 22, coil of relay 18, conductor 23, contact 24 to ground. It will be noticed that relay 25 was energized when

the operator inserted the plug 8 into jack 3 by the closure of the following circuit: battery, coil of relay 25, conductor 26, sleeve side of plug 8 and jack 3 respectively, coil of relay 6 to ground. It will also be noted that during the application of the ringing current to the called subscriber's line, the 70 75 lamp 19 and the relay 18 are connected in series and, due to this fact, the brilliancy of the lamp 19 will be below normal or less than when no resistance is included in its energizing circuit. This feature may serve as a 80

signal for notifying the operator that ringing current is being sent over the line of subscriber B.

Upon the removal of the receiver by the subscriber at substation B, enough resistance 85 is removed from the line circuit to operate the marginal relay 30, which is energized over the following path: from a source of alternating current through the coil of relay 30, contact 31, ring side of plug 8 and jack 3 90 respectively, line wire 1, through the substation B, returning over line wire 2, tip side of the jack 3 and plug 8 respectively, contact 32 to ground. The energization of the relay 30 removes the short circuit normally 95 about the relay 33, thereby permitting its operation over the following path: battery, resistance 34, coil of relay 33, conductor 35, 36, contact 24 to ground. The energization of the supervisory relay 10 takes place simultaneously with the energization of the relay 30. It may be mentioned here that the relay 30 is of a slow releasing type so as to allow sufficient margin to insure the operation of the relay 33. The operation of the relay 33, 100 in pulling up its right-hand armature, opens its back contact 21 and closes its front contact 37. The opening of contact 21 effects the deenergization of the ringing relay 18 and the extinction of the lamp 19. The ex- 110

tinguishing of the lamp 19 may serve as a signal to the operator that the called subscriber has responded. By the opening of contact 38 the short circuit about the relay 33 is permanently removed until it becomes deenergized.

When the subscribers A and B have finished conversing, upon the replacement of the receiver at substation B, the supervisory relay 10 is deenergized, which in releasing its armature permits the closure of contact 42, thus establishing the following circuit through the lamp 19: battery, lamp 19, conductor 20, contact 37, conductor 43, contact 42 to ground. It will be noted that the lamp 19 can now burn at its full brilliancy due to the fact that no resistance is included in the circuit just described. The operator upon observing the lighting of the lamp 19 will be informed that the subscriber at substation B has replaced his receiver upon the switch-hook. The replacement of the receiver by subscriber A will effect the lighting of the lamp 14 by the closure of the following circuit: battery, contact 50, conductor 51, contact 24, to ground. The lighting of the lamps 14 and 19 will indicate to the operator that she is now at liberty to take down the connection existing between the subscribers A and B.

From the above it will be apparent that by controlling the strength of current flowing through a signaling device, a plurality of indications may be obtained from the same device, and each indication may function as a signal for a distinct operation on the part of the operator. By virtue of the fact that one of these indications is present during the application of ringing current to the line of the called subscriber, the supervisory work of the operator is greatly relieved by eliminating the necessity of her going in on the line of the called subscriber to ascertain its condition.

45 What is claimed is:

1. In a telephone system, a subscriber's line, a link circuit, a source of ringing current, a relay for connecting said source to the line, a signaling device, an operating circuit for and including both the relay and the signaling device completed upon connection of the link circuit with the line, means in the link circuit and controlled from the station on the line for opening the operating circuit, a second operating circuit for the signaling device, and means controlled from the station on the line for completing the second operating circuit.

2. In a telephone system, a subscriber's line, a link circuit, a source of ringing current, a relay for connecting said source to the line, a signaling device, an operating circuit for and including both the relay and

the signaling device completed upon connection of the link circuit with the line, means 65 in the link circuit and controlled from the station on the line for opening the operating circuit, a second operating circuit of substantially lower resistance than the first operating circuit for the signaling device, 70 and means controlled from the station on the line for completing the second operating circuit.

3. In a telephone system, a subscriber's line, a link circuit, a source of ringing current, 75 a ringing relay for connecting said source to the line, a signaling device, an operating circuit for and including both the ringing relay and the signaling device completed upon connection of the link circuit 80 with the line, a relay in the link circuit operating upon removal of the receiver from the switchhook at the station on the line for opening the operating circuit and excluding the ringing relay therefrom, a supervisory 85 relay, and an operating circuit for the signaling device alone completed upon the deenergization of the supervisory relay.

4. In a telephone system, a subscriber's line, a link circuit, a source of ringing current, 90 a ringing relay for connecting said source to the line, a signaling device, an operating circuit for and including both the ringing relay and the signaling device completed upon connection of the link circuit 95 with the line, a relay in the link circuit operating upon removal of the receiver from the switchhook at the station on the line for opening the operating circuit, a supervisory relay, and a second operating circuit for the 100 signaling device of substantially lower resistance than the first operating circuit completed upon the deenergization of the supervisory relay.

5. In a telephone system, a subscriber's 105 line, a link circuit, a source of ringing current, a ringing relay for connecting said source to the line, a signaling device in the link circuit, an operating circuit for and including both the ringing relay and the 110 signaling device completed upon the connection of the link circuit with the line, a relay in the link circuit operating upon the removal of the receiver from the switchhook at the station on the line for opening 115 the operating circuit, a supervisory relay, and a second operating circuit for the signaling device of substantially lower resistance than the first operating circuit partially established upon the operation of the 120 second-mentioned relay and completely established upon the subsequent deenergization of the supervisory relay.

In witness whereof, I hereunto subscribe my name this 15th day of July, A. D. 1915. 125
EDWARD E. HINRICHSEN.
